UNITED STATES PATENT OFFICE.

CHARLES W. SHARTLE, OF MIDDLETOWN, OHIO.

APPARATUS FOR SALVAGING USABLE MATERIALS FROM STREET SWEEPINGS AND DUMP STOCK.

Application filed June 17, 1920. Serial No. 399,686.

To all whom it may concern:

Be it known that I, CHARLES W. SHARTLE, a citizen of the United States, residing at Middletown, in the county of Butler and State of Ohio, have invented certain new and useful Improvements in Apparatus for Salvaging Usable Materials from Street Sweepings and Dump Stock; of which the following is a specification, reference being had therein to the accompanying drawing.

This invention relates to an improved apparatus for salvaging usable materials from street sweepings and dump stock, having particular reference to stock which may be reclaimed and reduced to pulp for making paper and other products of various kinds and grades.

Careful investigations and tests made show that but a small percentage of such materials are reclaimed by the present common practice of salvaging.

The reclaiming and reducing apparatus of the present invention consists of various units of machinery arranged in such relation one with another that the operations of reclaiming and reducing the stock are in effect a continuous process from the introduction of the dump stock to the first unit of the machinery to the completion of the finished pulp in the last unit of the machinery.

When certain predetermined uses are to be made of the reclaimed stock, it is desirable at times to obtain a grading of the pulp made therefrom. Thus non-fibrous materials, such as all kinds of scrap paper and paper board and the general run of street sweepings will become separated from the mass of material in the reduction processes and will constitute a relatively low grade of stock; while fibrous materials, such as rags and fabrics of every description, will constitute a relatively high grade of stock,—the different grades being separated and reduced to finished pulp in the normal operation of the apparatus.

It is a further purpose of the invention to provide in the normal operation of the apparatus for reclaiming metals, glass and all kinds of irreducible materials contained in the dump stock which have value for further use.

As far as I am aware the present invention is the first of this general character that has been brought to practicable or commercial operation. The different units of

the machinery comprised in the apparatus are similar to pulp-making machinery generally but the order of their arrangement and coordination one with another, and the apparatus as a whole are believed to be broadly new in this art.

In the drawings:

Fig. 1 is a general plan view of the apparatus in one form of construction embodying the invention;

Fig. 2 is a side elevation of a raw stock breaker of modified construction, as used in the invention;

Fig. 3 is a side elevation of a pulp thickener of ordinary construction, the illustration of the drawing being more or less conventional; and

Fig. 4 is a detail view illustrating a special feature of the breaker and beater as used in the apparatus.

The apparatus consists, as here shown in Fig. 1, of a conveyor A which may be of any suitable construction, preferably of the endless carrier type; a stock duster or sifter B, of any suitable type wherein the fine dirt is separated from the miscellaneous assortment of stock therein; a disintegrator C which may be of either rotary or stationary type, arranged in series with the sifter B to receive the stock therefrom, and in which the stock is cooked or steam heated to effect disintegration of the reducible portions thereof; a settling trough D and whirl-pool D', the whirl-pool being in effect a feature of the settling trough through which the stock as discharged from the disintegrator C moves by gravity flow and in which heavy materials, such as metal, glass, etc., separate from the mass and settle to the bottom of the trough, and light substances unfit for use rise to the surface of the mass in the whirlpool where they may be skimmed off; a beater E which receives the stock from the whirl-pool and acts upon it by continuous grinding to reduce the same to required fineness; a thickener F which receives the stock from the beater E and acts upon it to extract the greater portion of the water therefrom to reduce the stock to required consistency; and a pump G which returns the water from the thickener to the settling trough.

As shown in Fig. 2 the raw stock breaker H is of the usual construction used in pulp reducing apparatus, and consists of a tub or

tank 1, breaker roll 2, blades 3 and bed block 4. A partition 5 extends longitudinally through the center of the tub, thus dividing the tub into two opposite channels. The breaker roll is mounted in one of the channels only and thus acts in the operation of the breaker to cause all the material to circulate in the tank and to pass repeatedly under the breaker blades which are of heavy construction and dull and do not materially affect the fibrous material, but act to break up and reduce the non-fibrous material to the required fineness. The breaker may be operated from any suitable source of power by means of the belt connection 6.

The beaters E E' illustrated in Figs. 1 and 2 correspond generally in construction to the breaker H, consisting as here shown of the tub 7, beater roll 8, dividing partition 9 and belt connection 10. Beater blades are arranged in the roll 8 substantially in the same manner as in the breaker roll 2, except that the blades are relatively sharp and have a direct grinding action on the stock, thus acting to reduce the fibrous material as well as the non-fibrous by the continuous grinding thereof.

The special feature shown in Fig. 4 consists of a device known in pulp manufacturing as a perforated back-fall plate. The device of itself constitutes the subject matter of U. S. Letters Patent No. 1,271,426, issued to Brownell Buehler, July 2nd, 1918. This invention consists of a perforated plate 11 arranged transversely in the tank of the beater or breaker and cooperating with the beater roll to effect the reduction of the stock to the required state of fineness to permit the same to pass through the apertures in the back-fall plate. Thus with the continuous operation of the beater the finished stock will be constantly flowing through the back-fall plate, and may then be delivered into any suitable receptacle for finished pulp.

The pulp thickener F as best shown in Fig. 4, is also of the usual construction, consisting of the tank 12, cylinder mold 13, couch roll 14, and scraper 15; the material being discharged from the scraper into a hopper 16 in which an agitator of any suitable construction may be operated through the connection 17 to maintain even mixture of the stock as it is transferred from the hopper to a stuff chest or other suitable receptacle for the finished pulp.

The disintegrator C, as shown, consists of a rotatable tank in which a longitudinal, spiral partition 18 is arranged. The tank may be charged in any suitable manner with hot water, or may be charged with cold water, means being then provided to heat the water, together with the raw stock in the tank, to effect disintegration of the reducible material as it follows the spiral course through the tank.

The sifter B may be of any suitable construction of rotary or reciprocating sieves or screens which will act to separate the fine dirt and dust from the raw stock, the present showing of the device being conventional only for illustrative purposes.

The pump G, also here shown conventionally, may be of any well known construction suitable for the requirements of the apparatus.

In the construction shown in Fig. 1 the operation of the apparatus and processes of reduction are substantially as follows:—

The raw dump stock is delivered to the screened sifter or duster B in any suitable manner, as by the endless belt or carrier A. In the sifter the stock is agitated by rotation of the device, where rotary screens are used, or by reciprocation, where reciprocating screens are used, thus effecting the elimination of dust and fine dirt from the stock before the same is delivered into the disintegrator C.

It is here noted that for certain grades of pulp made from dump stock, or more especially for certain finished products to be made of it, sifting or screening of the stock will not be required as all reducible material may be used. The disintegrator C will then be charged with the raw stock direct from the carrier A or other suitable means of conveying the stock thereto.

In the disintegrator, as above stated, the required amount of water is mixed with the stock, the water being heated either before or after it is charged into the tank to effect disintegration of the reducible material therein, reduction of the material being further aided by the operation of the device. The movement of the material from the endless carrier A to the sifter B and from the sifter to and through the disintegrator C to the settling trough is, preferably, continuous. However, in modified forms of construction means may be provided to interrupt the movement of the material at the point of discharge of any of the devices A, B and C.

In the settling trough D the material is further charged with water from the pump G, the mass of material flowing through the trough slowly to the whirl-pool D'. During this movement of the material heavy foreign substances, such as metals, glass, rocks, etc., will become separated from the mass by gravitation and will accumulate in the bottom of the trough where the same may be removed at any time or at suitable intervals when operation of the apparatus is stopped.

In the whirl-pool D' the material has an agitated or slow whirling movement which may be effected entirely by the gravity flow of the material or with the aid of mechanical agitators with which the pool may be

equipped. As a result of this movement light foreign substances, which may not be reduced or used for pulp, will rise to the surface of the mass and may be skimmed off and removed therefrom.

From the whirl-pool the stock flows continuously into the beater E where it is subjected to constant grinding which acts to reduce both the fibrous and non-fibrous materials until the entire mass is fine enough to pass through the back-fall plate 11, into an overflow box E' and thence into the thickener F.

In the thickener or extractor F the material engages the rotating cylinder mold 13 in a thin layer, and is carried up by the cylinder under the couch roll 14 which acts to press the greater portion of the water from the pulp. The material is scraped off the couch roll by a scraper 15 and is delivered into a hopper 16. From the hopper the material may be transferred in any suitable manner to a stuff chest for the finished pulp. The water from the thickener flows into the pump G and is thence returned to the settling trough.

From the foregoing detailed description and accompanying drawings, the construction, operation and results of operation of the apparatus will be readily understood by those experienced in the art of pulp production. It will be observed that the construction and operation of the apparatus is in effect a continuous system of reduction.

It will be understood that the respective units of the apparatus may be arranged at different elevations relative to each other to effect the desired movements of the material from one unit to another.

Having thus fully described my invention, what I claim as new and desire to secure by Letters Patent, is:—

1. In a reducing apparatus for making pulp, the combination of a sifter and means to deliver raw stock thereto, a disintegrator in series with the sifter and adapted to receive the stock therefrom, and means comprising a settling trough, a finishing beater into which said trough delivers its whole floatable contents, and a thickener into which said finishing beater delivers reduced material, all arranged in series with said disintegrator and cooperating therewith to effect reduction of said stock.

2. In a reducing apparatus for making pulp, the combination of a disintegrator and means to deliver raw stock thereto, and means comprising a settling trough, a finishing beater into which said trough delivers its whole floatable contents, and a thickener into which said finishing beater delivers reduced material, all arranged in series with said disintegrator and cooperating therewith to effect reduction of said stock.

3. In a reducing apparatus for making

pulp, the combination of a disintegrator having a spiral channel arranged therein, means to cause raw stock charged with water to be delivered through said channel, and means comprising a settling trough, a finishing beater into which said trough delivers its whole floatable contents, and a thickener into which said finishing beater delivers reduced material, all arranged in series with said disintegrator and cooperating therewith to receive said stock and to effect further reduction thereof.

4. In a reducing apparatus for making pulp, the combination of a rotatable sifter and a rotatable disintegrator arranged in series with the sifter and adapted to receive stock therefrom and an endless carrier cooperating with the sifter to deliver raw stock thereto, said devices being continuous in operation, and means comprising a settling trough, a finishing beater into which said trough delivers its whole floatable contents, and a thickener into which said finishing beater delivers reduced material, all arranged in series with said disintegrator and cooperating therewith by continuous operation to effect reduction of said stock.

5. In a reducing apparatus for making pulp, the combination of a raw stock disintegrator and a settling trough cooperating therewith by receiving stock therefrom, a finishing beater cooperating with the settling trough by directly receiving therefrom all of the floatable stock treated in said trough and acting to effect final reduction thereof, and a pulp thickener cooperating with the finishing beater to extract water from the finished pulp.

6. In a reducing apparatus for making pulp, the combination of a raw stock disintegrator and a settling trough cooperating therewith by receiving stock therefrom, and a finishing beater cooperating with the settling trough by directly receiving therefrom all of the floatable stock treated in said trough and acting to effect final reduction thereof.

7. In a reducing apparatus for making pulp, the combination of a raw stock disintegrator and a settling trough cooperating therewith by receiving stock therefrom, and a finishing beater cooperating with the settling trough by directly receiving therefrom all of the floatable stock treated in said trough, said finishing beater having means whereby pulp of predetermined fineness is continuously discharged therefrom.

8. In a reducing apparatus for making pulp, the combination of a raw stock disintegrator and a settling trough, cooperating with the disintegrator by directly receiving therefrom all of the stock treated in said disintegrator, said trough having a whirl-pool through which said stock flows,

and a finishing beater adapted to receive the stock directly from the whirl-pool and acting to effect final reduction thereof.

9. In a reducing apparatus for making pulp, the combination of a raw stock disintegrator and a settling trough cooperating therewith by directly receiving therefrom all of the stock treated in said disintegrator, a breaker cooperating with the settling trough by directly receiving said stock therefrom, and means in said breaker to effect separation of one grade of material from another of said stock.
10. In a reducing apparatus for making pulp, the combination of the following co-ordinated instrumentalities whereby continuous reduction is effected, a sifter adapted
- to receive raw stock and to remove dust and fine dirt therefrom, a disintegrator charged with water and cooperating with the sifter to receive said stock therefrom, a settling trough adapted to receive the stock from the disintegrator and wherein heavy foreign materials will gravitate to the bottom of said trough and light foreign materials will rise to the surface of the mass of material passing therethrough, and a finishing beater arranged to receive directly all of the floatable stock from the settling trough said finishing beater having means to effect final reduction thereof.

In testimony whereof, I affix my signature.

CHARLES W. SHARTLE.
